UNITED STATES PATENT OFFICE

133,565

DESIGN FOR A RUG OR THE LIKE

Walter Kansteiner, Cat Spring, Tex.

Application November 25, 1941, Serial No. 104,327

Term of patent 3½ years

To all whom it may concern:

Be it known that I, Walter Kansteiner, a citizen of the United States, residing at Cat Spring, in the county of Austin and State of Texas, have invented a new, original, and ornamental Design for a Rug or the like, of which the following is a specification, reference being had to the accompanying drawing, forming part thereof.

The figure is a plan view of a rug or the like showing my new design.

I claim:

The ornamental design for a rug or the like, as shown.

WALTER KANSTEINER.
